ISOLATING HANGER

Frederick M. Venzie, Philadelphia, Pa., assignor
to National Gypsum Company, Buffalo, N. Y.,
a corporation of Delaware

Application February 25, 1933, Serial No. 658,518

14 Claims. (Cl. 72—118)

My invention relates to building construction and more particularly to isolating hangers adapted to support a ceiling structure from a floor construction.

5 It has for some time been realized that a rigid link between a floor and suspended ceiling has been unsatisfactory due to the sound reflecting and transmitting character of such links. Attempts heretofore made to overcome this disadvantage have resulted in the adoption of various hangers of a resilient type or of a type in which two parts were separated by a single layer of felt. Neither of these types of hangers are completely satisfactory due to the fact, in the first 10 instance, that there is a continuous metal to metal contact between adjacent elements in spite of the resiliency, and, in the second instance, to the fact that where only a single layer of felt is interposed between two pieces of metal there is no true resiliency and the felt promptly wears through and leaves a metal to metal contact.

20 My invention comprises an isolating hanger in which not only are the parts of the hanger relatively movable but in which, between adjacent metal parts, are arranged layers of a resilient and sound absorbing material.

25 An object of the invention is to provide a novel form of isolating hanger in which is broken a through metal to metal contact between the floor and a ceiling suspended thereby.

30 Another object of my invention is to provide a novel hanger in which a resiliency is interposed between a supporting floor and a ceiling supported thereby.

35 Yet another object of my invention is to provide a novel isolating hanger in which not only is the connection between a supporting floor and a supported ceiling made resilient but also the continuous metal connection between the floor and a ceiling is broken by a non-metallic link.

40 Other objects and advantages of my invention will be apparent from the following specification, claims, and from the drawing, in which:

45 Fig. 1 is a side elevation, partially in section, on the line 1—1 of Fig. 2, showing one embodiment of my invention as employed in supporting a ceiling from a floor construction.

50 Fig. 2 is an elevation, partially in section, on the line 2—2 of Fig. 1, of the embodiment of my invention shown therein;

55 Fig. 3 is an enlarged vertical elevation taken on the line 3—3 of Fig. 2, showing in detail the hanger;

Fig. 4 is an elevational view, partially in section, of a modified form of my invention;

Fig. 5 is a horizontal sectional view taken on the line 5—5 of Fig. 4; and

Fig. 6 is a detail view of yet another embodiment of my invention.

The isolating hangers comprising my invention and illustrated in Figs. 3 to 5 inclusive each is for the same purpose and may be similarly attached or connected to a ceiling, and they, as well as the embodiment shown in Fig. 6, may be similarly connected to a floor. Referring particularly to Figs. 1 to 3 inclusive, a floor F of concrete or similar material when being formed about reinforcing R may be poured about a metallic strap 10, preferably having in its upper end a right angle bend 11. To this strap the 15 hangers embodying my invention may be thereafter connected as hereinafter described, or the hanger may be attached to the strap prior to the pouring of the concrete. To the lower end of the hanger a strap 23 is connected which in turn supports light channels 43 which in turn support, by means of links 45, cross furring members 46 to which suitable panels 47 may be directly connected.

Referring now to the embodiment of my invention illustrated in Figs. 1 to 3, a hole 12 is made in the strap 10 adjacent its lower end through which may be passed a bolt 13 having on one end a nut 14. Each end of two composite flexible strips 15—15 is perforated to allow passage 20 therethrough of the bolt 13, the strips being mounted upon the bolt on either side of the strap 10 and each spaced therefrom by washers 16 which may be of a suitable resilient and non-metallic nature such as felt, brake lining, leather, 25 or the like. The resilient strips 15 comprise inwardly facing portions 15a of brake lining or other similar material of high tensile strength and fire-resisting characteristics, and each of these strips may be backed by a thin layer of 30 metal 15b such as sheet brass. The lower ends of the strips 15 are perforated similarly to the upper ends and these are connected by a bolt 20 and nut 21 and spaced therefrom by resilient and non-metallic washers 22 to a vertical strap 23 35 which extends downwardly below the ends of the strips 15. As illustrated, the centers of the holes in opposite ends of the backing 15b are spaced slightly further apart than are the holes in the inner portions 15b so that no tensile stress 40 is exerted on the metal strips. These are designed solely as a safety measure for use only if the straps should be burnt. Interposed between the inner opposite faces 15a of the strips 15 is an 45 expansion spring 25 held in location by oppositely 50 tensioned washers 26. The bolt 20 is held in position by a lock washer 27 and a lock nut 28. The 55 vertical strap 23 is connected to the strap 10 by a bolt 30 and nut 31.

facing caps 26 which may be held in position by rivets 27 passing therethrough and through preferably only the inner portion 15a of the strips 15.

The embodiment of my invention shown in Figs. 4 and 5 may be attached to the floor and to the ceiling supporting structure similarly to that shown in Figs. 1 to 3. In this embodiment, however, the strap 10 is connected by a bolt 30, passing through an opening in the lower end of the strap, and nut 31, to a U-shaped metallic member 32 lined with a non-conductive, non-metallic material 33 such as brake lining, leather, or the like. Since in this embodiment of my invention the metal supports the ceiling there is no requirement that the lining 33 necessarily be fireproof, although, under present day building requirements such construction is preferred. This material extends the full length of the metal member 32 and acts as a washer between the ends thereof and the strap 10, thus isolating the metal of the U-shaped member 32 from that strap. A member 35 and lining 36 both identical in construction with the members 32 and 33 passes through the latter at right angles thereto, and it is connected at its lower end by bolt 36 to the lower strap 23. Between the bottoms indicated at 32a and 35a of the U-shaped members 32 and 35 is interposed an expansion spring 38 spaced from the linings thereof at opposite ends by washers 39. From the foregoing description and from a consideration of the drawing it will be obvious that the metal contact between the adjacent U-shaped elements is broken and that resiliency is imparted to the hanger by the spring 38.

In the embodiment of my invention illustrated in Fig. 6 the strap 10 is connected to a member essentially similar in shape to that illustrated at 32 in Fig. 4, namely: a U-shaped member 40 within which, and preferably adhesively secured to the inner walls thereof, is a thick layer of felt 41 surrounding, adjacent the lower end of the U, a U-shaped frame 42 adapted to carry a channel member 43 which acts as a ceiling carrier. The channel member 43, or preferably the inner portion of the U-shaped frame 42, is lined with a layer of felt 44. In this embodiment of my invention it will appear that the metal to metal contact is broken not only by the felt lining 41 but also by the lining 44. These two linings are maintained out of contact with each other and the wear of the channel members spread over a large portion of felt lining 41, by the inner U-shaped member 42.

Various modifications may be made in the above described embodiments of my invention without departing from the spirit or scope thereof as set forth in the following claims.

What I claim is:

60 1. An isolating hanger comprising suspending means adapted for fixed attachment to a support; means for supporting a ceiling; a metal spring forming a portion of a linkage between said suspending means and said supporting means; and a non-metallic connection in said linkage between two metallic parts thereof.

70 2. In an isolating hanger adapted to connect a ceiling structure to a vertically spaced support, a metal spring adapted to expand and contract to vary the distance between the ceiling and its support upon the application of pressure to said ceiling, and a non-metallic connection interposed between two metal parts of said hanger whereby a through metal connection between 75 said support and said ceiling structure is broken,

3. An isolating hanger comprising means adapted for permanent attachment to a support; means adapted for attachment to a ceiling; linkage between said first two named means comprising flexible non-metallic strips and means for imparting resiliency to said hanger; and means connecting opposite ends of said strips to said first two named means. 5

4. An isolating hanger comprising a metal strap adapted to be embedded in a concrete floor; a metal strap adapted for connection to ceiling supporting members; and linkage between said straps comprising two leather straps, said leather straps having their faces in opposed relationship, a metal backing strip adjacent the outer face of each of said leather straps, means for connecting said leather straps and metal backing strips adjacent opposite ends to the metal straps, said metal backing strips being so connected that no strain is imposed thereon, cup-shaped caps riveted to said leather straps with their cup-shaped faces in opposed relationship, and an expansion spring positioned in the cup-shaped faces of said caps and at right angles to the inner faces of said leather straps whereby resiliency is imparted to said hanger. 20

5. An isolating hanger comprising a metal strap adapted to be embedded in a concrete floor; a metal strap adapted for connection to ceiling supporting members; and linkage between said straps comprising two non-metallic straps, said non-metallic straps having their inner faces in opposed relationship, a metal strip, means for connecting said non-metallic straps and metal strips adjacent opposite ends to the metal straps, said non-metallic straps being interposed between said metal strips and said metal straps, and an expansion spring positioned between the opposed inner faces of said non-metallic straps. 30

40: 6. An isolating hanger comprising a metal strap adapted to be embedded in a concrete floor, a metal strap adapted for connection to ceiling supporting members, and linkage between said straps comprising two non-metallic flexible straps, said flexible straps having their inner faces in opposed relationship, means for connecting the ends of said flexible straps to said metal straps, and means for imparting resiliency to said hanger. 45

7. An isolating hanger comprising a metal strap adapted to be embedded in a concrete floor, a metal strap adapted for connection to ceiling supporting members, and linkage between said straps comprising two non-metallic flexible straps, said straps having their inner faces in opposed relationship, means for connecting the ends of said flexible straps to the metal straps, and an expansion spring positioned between the opposed inner faces of said flexible straps whereby resiliency is imparted to said hanger. 50

8. An isolating hanger comprising a metal strap adapted to be embedded in a concrete floor, a metal strap adapted to be attached to ceiling supporting means, and means for connecting said straps comprising two U-shaped links each link comprising a U-shaped metallic member with a U-shaped leather lining completely covering its inner face, one of said U-shaped links being arranged at right angles to the other with its base passing through the open portion of the other, whereby a substantially box-shape structure is formed, a metallic washer within each of the bases of each of the U-shaped pieces, an expansion spring interposed between said washers, 70

75

and means for connecting the open end of each of said U-shaped links to one of said straps.

9. An isolating hanger comprising a metal strap adapted to be embedded in a concrete floor, a metal strap adapted to be attached to ceiling supporting means, and means for connecting said straps comprising two U-shaped links each link comprising a U-shaped metallic member with a U-shaped non-metallic inner lining, one of said 10 U-shaped links passing through the other, means for connecting the open end of each of said links to one of said straps, and an expansion spring interposed between said links.

10. An isolating hanger comprising a metallic strap adapted to be embedded in a concrete floor, a metallic member adapted to support a ceiling, and linkage between said strap and said metallic member comprising a resilient felt material surrounding said metallic member, a U-shaped metallic clip surrounding said felt, and a felt lined U-shaped member of larger size than said first named U-shaped member surrounding said U-shaped metallic member, and means for fixedly securing said last named member to said first 25 named strap.

11. An isolating hanger comprising a metallic strap adapted to be embedded in a concrete floor, a metallic member adapted to support a ceiling, and linkage between said strap and said metallic member comprising a resilient non-metallic material surrounding said metallic member, a U-shaped metallic clip surrounding said non-metallic material, and a U-shaped member of 30 larger size than said first named U-shaped member and lined with a non-metallic material sur-

rounding said U-shaped metallic member, and means for fixedly securing said last named member to said first named strap.

12. An isolating hanger comprising a strap adapted to be embedded in a concrete floor, a metallic member adapted to support a ceiling, and linkage between said strap and said metallic member comprising a resilient material surrounding said metallic member, a U-shaped metallic clip surrounding said resilient material, and a 10 U-shaped member of larger size than said first named U-shaped member surrounding said first named U-shaped member, a non-metallic lining adhesively secured thereto, and means for fixedly securing to said first named strap said last named 15 U-shaped member.

13. An isolating hanger comprising a strap adapted for permanent attachment to a floor; means for supporting a ceiling; a non-metallic substance; and a metal spring interposed between 20 said strap and said ceiling supporting means, said metal spring being maintained out of contact with said strap by the interposition of said non-metallic substance between the two.

14. An isolating hanger comprising a strap 25 adapted for permanent attachment to a floor; means for supporting a ceiling; a non-metallic substance; and a metal spring interposed between said strap and said ceiling supporting means, said metal spring being maintained out of contact with said ceiling supporting means by the 30 interposition of said non-metallic substance between the two.

FREDERICK M. VENZIE. 35
